UNITED STATES PATENT OFFICE.

FRED H. DANIELS, OF WORCESTER, MASSACHUSETTS, ASSIGNOR TO RILEY STOKER CORPORATION, OF WORCESTER, MASSACHUSETTS, A CORPORATION OF MASSACHUSETTS.

PULVERIZING APPARATUS.

Application filed August 21, 1926. Serial No. 130,749.

This invention relates to pulverizing apparatus, and more particularly to an apparatus of the beater type.

Such a machine is disclosed in the reissue 5 patent to Blyth, No. 16,229, in which material is comminuted by the action of interfitting alternately revoluble and stationary impact bodies or pegs. An arrangement of this type is very efficient in producing fine 10 pulverization, but has certain inherent defects. It is found that the power consumption is excessive when operating upon coarse materials, and the pegs are subject to rapid wear. Moreover, the pegs are relatively 15 fragile, and are easily broken by hard foreign bodies, such as tramp iron, which are frequently present in certain materials.

It is accordingly one object of my invention to provide a pulverizing apparatus in 20 which coarse material may be efficiently reduced to a desired degree of fineness.

A further object of my invention is to provide a pulverizing apparatus which is so arranged that hard foreign bodies entering 25 the machine may be safely eliminated without damage to the pulverizing elements.

With these and other objects in view, as 30 will be apparent to one skilled in the art, my invention resides in the combination of parts set forth in the specification and covered by the claims appended hereto.

According to my invention, I provide a 35 pulverizing apparatus in which a crushing roll is arranged for pulverizing the material preliminarily and then feeding it for fine pulverization to a second zone. In my preferred embodiment I make use of a pair of crushing rolls so constructed as to crush the material between them. It is desirable to 40 prevent damage to the rolls caused by hard foreign bodies, and one way in which this may be accomplished is by mounting one roll yieldingly by a suitable means, such as a spring. The material thus crushed preliminarily is fed at a regulatable rate to the 45 periphery of a second zone containing revoluble beaters and it is there forced by a fan to pass towards a centrally located outlet against the centrifugal forces set up by the revolving beaters. In the preferred construction, the material is finely pulverized by alternately revoluble and stationary impact members as it passes towards the central outlet. In order to protect these rap-

idly revolving impact members from tramp 55 iron which might enter the casing with the coarse material and cause serious damage, provisions are made for eliminating such large hard foreign bodies. To this end, I space the crushing rolls from the peripheral 60 path of the revolving impact members and provide room for such bodies to settle out of the entering stream and fall into a receptacle at the bottom of the casing, from which they may be removed through a trap 65 door. A fan may be so located as to draw the material thru the machine on a current of air of desired volume. Revoluble re-jector blades may be arranged to sweep 70 across the exit opening and hurl back into the machine any coarse particles which attempt to pass, thus serving to keep the product uniformly fine.

Referring to the drawings in which like reference numerals indicate like parts:

Fig. 1 is a vertical section through the machine, illustrated somewhat diagrammatically, the section being taken on the line 1—1 of Fig. 2;

Fig. 2 is a section on the line 2—2 of Fig. 1;

Fig. 3 is an elevation showing the arrangement of gears for connecting the rolls; and

Fig. 4 is a view similar to Fig. 3, with the gears removed for clearness of illustration.

The embodiment of my invention illustrated in the drawings comprises a casing arranged to form a grinding chamber 10 connected by a central passage 11 to a fan chamber 12. A horizontal shaft 14 extends 90 through both chambers, and is rotatably mounted in suitable bearings, illustrated diagrammatically as bosses 16 and 17 on the casing. This shaft may be rotated by any suitable source of power.

I have found a toothed crushing roll to be very efficient in crushing material preliminarily. While one such roll can be utilized to crush material against a fixed abutment, I prefer to make use of a pair of rolls 20 and 21 arranged beneath a hopper 22. These rolls are keyed to rotatable shafts 24 and 25, respectively. These shafts may be rotated by any suitable device, and it is desirable that means be provided for varying their speed, as the load on the machine may vary. This serves to vary the rate of feeding the coarse material to the second zone. Accord-

ing to the simple form of construction illustrated, shaft 25 is driven from shaft 14 by a belt 27 passing over cone pulleys 29 and 30. Shaft 24 is provided with spur gears 32 which mesh with similar gears 33 on shaft 25. The power mechanism illustrated causes the impact members 41 and the crushing rolls to revolve at a definite speed ratio, and this ratio may be varied by shifting the belt 27 on the pulleys so that it is possible to vary the rate of feeding the material to the revolving impact members without changing their speed. In order to permit roll 20 to yield when necessary to prevent damage from foreign bodies, shaft 24 may be mounted at each end in a bearing 35 arranged to slide horizontally away from shaft 25. Such movement is normally prevented by any suitable means such as spring 36, as shown in Fig. 4, located between each bearing 35 and a fixed part of the casing. A suitable pocket 38 may be provided in the casing to catch any hard foreign bodies which pass the rolls. A slide 39 permits such bodies to be removed when desired.

In order to further pulverize material delivered by the rolls, I utilize revoluble impact members. These members may take the form of pegs 41 mounted in concentric circles on a disk 42 which is keyed to the shaft 14. These pegs may cooperate with stationary pegs 44 mounted on the casing wall. Although any suitable method of mounting the pegs may be used, the preferred construction is fully disclosed in the patent to Riley No. 1,576,472. If desired, a set of rejector blades 46 may be mounted on a hub 47 which is keyed to the shaft 14. These blades may be arranged to sweep across the outlet opening 11, and throw back into the pulverizing chamber any coarse particles which reach them. In order to assist in this action, a beveled ring 48 may surround the blades.

Material is preferably carried through the machine on a current of air, which may be produced by a suitable fan 50, mounted on the shaft 14 in chamber 12. Air may enter the machine through an opening 51 located at any desired point in the casing. Air and pulverized material may leave the fan chamber through a tangential outlet 52.

The operation of my invention will now be apparent from the above disclosure. Coarse material is delivered to the hopper 22 by any suitable feeding device. Shafts 24 and 25 are driven from shaft 14 which in turn is rotated by any suitable source of power. Material is crushed by the rolls 20 and 21, and any hard foreign bodies will separate the rolls, pass through, and drop into pocket 38. Crushed material is drawn by the air current produced by fan 50, and passes against centrifugal force among the pegs 41 and 44, where it is finely pulverized by impact. Fine material passes into the fan

chamber and out through opening 52. Coarse particles reaching the rejectors 46 are returned to the machine for further treatment.

It will be apparent to one skilled in the art that this invention provides an efficient pulverizing apparatus which will reduce coarse material to a desired degree of fineness without excessive power requirements and without causing undue wear to the machine. The preliminary crushing is accomplished by rolls especially constructed to eliminate damage from hard bodies. The impact pegs are protected from contact with such hard bodies, and are utilized only for so fine grinding, for which purpose they are eminently adapted.

Having thus described my invention, what I claim as new, and desire to secure by Letters Patent, is:

1. A pulverizing apparatus comprising a casing having an inlet and an outlet, a pair of rotatable crushing rolls arranged to crush coarse material, means to rotate said rolls, means to permit one of said rolls to yield and allow hard foreign bodies to pass without damage, a pocket suitably located to receive such hard bodies, and revoluble impact members arranged to receive material from said rolls and pulverize said material finely. 95

2. A pulverizing apparatus comprising a casing provided with an inlet for material and a centrally disposed outlet, revoluble and stationary impact members arranged adjacent to said outlet to produce fine pulverization of material fed thereto, a pair of crushing rolls arranged adjacent to the inlet to receive and crush the coarse material, means to hold said rolls normally in an operative position, means to permit one of said rolls to yield and allow the passage of hard foreign bodies without damage, a receptacle suitably disposed to receive such foreign bodies and prevent their coming into contact with the impact members, and means to transport material against the centrifugal action of said impact members towards said centrally disposed outlet. 105

3. A pulverizing apparatus comprising a casing having an inlet conduit and a centrally located outlet, a series of beaters therein revolving about the outlet which are so arranged that the pulverized material must pass inwardly to the outlet against the successive impacts and the outwardly impelling action of the beaters, and means including a crushing roll in the inlet conduit to feed crushed material directly to the periphery of the path of said beaters. 115

4. A pulverizing apparatus comprising a casing having an inlet and an outlet, revoluble impact members therein to pulverize material fed thereto, and means including a yieldingly mounted crushing roll spaced from the path of said members and arranged

to feed crushed material thereto but prevent large foreign bodies from contacting therewith.

5. A pulverizing apparatus comprising a casing having an inlet and an outlet, a set of revoluble impact members arranged to pulverize the material finely, means including a rotatable crushing roll to crush coarse material preliminarily and feed it to the impact members, power mechanism to revolve said impact members and to rotate the crushing roll at a definite speed ratio and means to vary the speed ratio.

6. A pulverizing apparatus comprising a casing having an inlet and an outlet, revoluble impact members therein to pulverize material fed thereto, a rotatable crushing roll spaced from the path of said members and arranged to feed crushed material directly thereto, yieldable means permitting large foreign bodies to pass said roll with

the material, and a receptacle arranged to catch such foreign bodies and prevent their contacting with said impact members.

7. A pulverizing apparatus comprising a casing having a centrally located outlet, a rotor therein having its axis passing through the outlet, rapidly revoluble impact pegs on the rotor cooperating with stationary pegs on the casing to pulverize the material passing inwardly towards the outlet, means providing an inlet for material to the peripheral path of the rotor pegs, means including a rotatable crushing roll to crush coarse material preliminarily for pulverization by said pegs, and means to pass a current of air through the apparatus from the inlet towards the outlet and remove the finely pulverized material therefrom.

Signed at Worcester, Mass., this 20th day 40 of August, 1926.

FRED H. DANIELS.
